his ATTORNEY

UNITED STATES PATENT OFFICE.

HENRY A. DENZIN, OF ROSS TOWNSHIP, ALLEGHENY COUNTY, PENNSYLVANIA.

HEATING-FURNACE.

No. 868,974.

Specification of Letters Patent.

Patented Oct. 22, 1907.

Application filed November 22, 1906. Serial No. 344,632.

To all whom it may concern:

Be it known that I, HENRY A. DENZIN, a citizen of the United States, residing in the township of Ross, in the county of Allegheny and State of Pennsylvania, 5 have invented or discovered new and useful Improvements in Heating-Furnaces, of which the following is a specification.

My invention consists of certain new and useful improvements in hot air heating stoves and furnaces, 10 especially relating to the use of natural or artificial gas as the heating agent. The mutual relation and position of the hot fume and air heating chambers is such that the largest possible percentage of heat is obtained from the fumes before they are delivered to the escape 15 pipe, the same being led and baffled about the walls of the hot air flues or chambers through which the air is allowed to rise unobstructedly so that entire wall area of the air chamber is heated.

In the accompanying drawings, Figure 1 is a vertical 20 section through furnace and outer casing, the burner being shown in full, Fig. 2 is a sectional plan along the line 11—11 in Fig. 1 and Fig. 3 is a perspective of the burner.

The following is a detailed description of the drawings: 1 is the outer casing which for convenience is made in two sections joined together horizontally as at 1^a.

2 is the top or cover of the casing thus forming a hot air chamber 3 in the upper part of the casing from which 30 lead hot air pipes 4—4 to the house registers or hot air flues, as the case may be.

The body of the furnace proper is composed of a plurality of concentric metal walls forming a plurality of concentric annular chambers surrounding a central 35 cylindrical chamber. The outer chamber 5, which is a fume chamber, is closed at top and bottom. The chamber 6, next within, is an air heating chamber open at top and bottom. The chamber 7, next within, is a fume chamber and closed at the top, while the central, 40 cylindrical chamber, 8, is an air heating chamber and open at top and bottom. The chamber 7 near its top is connected with chamber 5 by means of flue 9 crossing chamber 6, while diametrically opposite to flue 9 fume pipe 10, preferably of somewhat less diameter, leads 45 from the upper part of chamber 5 through casing 1 to the house chimney. On each side half way between the location of flue 9 and pipe 10 I provide baffles 11—11 which extend from wall to wall in the interior of chamber 5 from the top of said chamber to a point adjacent 50 to the bottom thereof, leaving a sufficient space, usually about six inches, for the passage of the fumes around the interior of the chamber.

The furnace body is supported from casing 1 by any convenient means as by bars 12—12, underneath said 55 body and attached at their ends to casing 1, any required number of the same being provided. The outer

wall of chamber 7 is extended downwardly to a point adjacent to the floor while the wall of chamber 8 is also extended downwardly to a somewhat less extent.

13 is a burner composed of a hollow annular body, 60 better shown in Fig. 3, which is supported by being slipped up over the lower extremity of the wall of chamber 8 and secured in place by any convenient means as by slightly flanging the lower edge of said wall. 14—14 are a plurality of holes punched in the outer 65 face of said burner to permit the escape of the gas which is ignited on said face in little jets or flames. Gas is supplied to said burner by pipe 15 entering through casing 1 and provided exterior to said casing with valve 16 and air mixer 17. 70

18 is a pipe supplying air to the face of burner 13 to aid in combustion.

The outer wall of chamber 7 is provided with an aperture 19, preferably square, which is connected by means of air tight box 20 to similar aperture 21 in the 75 casing 1. Aperture 21 is normally closed by door 22. By this means access may be had to the burner face for lighting the furnace while the air tight box prevents any products of combustion entering the interior of casing 1 in case of a back draft in the house chimney. 80

The operation of my furnace is as follows:—The hot fumes and products of combustion arising from the face of burner 13 rise in fume chamber 7 surrounding the outer wall of air heating chamber 8 and passing by means of flue 9 at the top into chamber 5 wherein 85 they pass downward under baffles 11—11 and up to pipe 10 whereby they escape into the house chimney. The air admitted into the interior of casing 1 by means of a fresh air duct or opening, not shown, passes up through the interior of air heating chambers 8 and 6 90 and the space between the casing 1 and the outer wall of chamber 5, into hot air chamber 3 whence it passes out into hot air pipes 4—4. It is evident that the fumes at their hottest surround air heating chamber 8 and move over the inner wall of air heating chamber 6 after which they are baffled over the entire surface 95 of the outer wall of said chamber 6, and at the same time heat the air passing upward in the space within the casing exterior to chamber 5. It is evident that the largest possible percentage of heat is thus extracted from the fumes and products of combustion before they are delivered to the house chimney. It is also evident that the entire wall area of the air heating chamber is subjected to the action of the hot fumes. There is therefore no dead wall space in the furnace. 100

The advantages of my novel construction are, *inter alia*, the thoroughness with which the vertical air passages or chambers are exposed to the heating power of the products of combustion. Also the extreme simpleness of my construction which may be quickly 110 constructed of sheet metal without the use of any cast parts. This enables me to effect a great saving in first

cost of materials and in time required for manufacture and erection.

Although I have described the construction shown in the accompanying drawings, I do not wish to limit myself thereby but claim broadly:

1. In furnaces, an outer casing and a furnace body contained therein consisting of a plurality of concentric annular walls forming a central air chamber, open at both ends, a fume chamber surrounding said central air chamber and closed at the top, a second air chamber surrounding said fume chamber and open at both ends, a second fume chamber surrounding said second air chamber and closed at both ends, a horizontal fume flue adjacent to the top of said body and adapted to conduct the fumes from said first fume chamber to said second fume chamber, a fume pipe leading from the top of said second fume chamber, diametrically opposite to said fume flue, to a point without said casing and an annular ring burner mounted on the inner concentric wall and directing the products of combustion against the inner wall of said second air chamber, substantially as described.

2. In furnaces, an outer casing and a furnace body contained therein and consisting of a plurality of concentric cylindrical walls, the two inner walls extending downwardly beyond the remainder of the furnace body, forming between the same first a central air chamber open at top and bottom, next encircling the same an annular fume chamber closed at the top, next encircling the same an annular air chamber open at top and bottom and next encircling the same an annular fume chamber closed at top and bottom; a horizontal fume flue leading from a point in said first fume chamber, adjacent to the top thereof, to said second fume chamber, a fume pipe leading from said second fume chamber to a point without said casing, diametrically opposite to said fume flue, baffles extending downwardly within said second fume chamber between said flue and said pipe, an annular burner body surrounding and mounted on the lower portion of said interior wall and having its exterior vertical face perforated for combustion so that the products of combustion

are thrown against the second interior wall, substantially as described.

3. In furnaces, an outer casing and a furnace body contained therein composed of a plurality of concentric walls forming a central cylindrical air chamber open at top and bottom, an annular fume chamber closed at the top next surrounding said central air chamber, an annular air chamber open at top and bottom next surrounding said fume chamber and a second fume chamber closed at top and bottom next surrounding said second air chamber, 45 said central air chamber and first fume chamber extending downwardly below the remainder of said furnace body, a fume flue connecting said fume chambers adjacent to the top thereof, a fume pipe, diametrically opposite to said fume flue connecting the second fume chamber to a point 55 without the outer casing and an annular burner body within said first fume chamber mounted on the base of said central air chamber.

4. In furnaces, an outer casing and a furnace body contained therein composed of a plurality of concentric walls forming a central cylindrical air chamber open at top and bottom, an annular fume chamber closed at the top next surrounding said central air chamber, an annular air chamber open at top and bottom next surrounding said fume chamber and a second fume chamber closed at top 60 and bottom next surrounding said second air chamber, said central air chamber and first fume chamber extending downwardly below the remainder of said furnace body, a fume flue connecting said fume chambers adjacent to the top thereof, a fume pipe, diametrically opposite to said 65 fume flue, connecting the second fume chamber to a point without the outer casing, an annular burner body within said first fume chamber mounted on the base of said central air chamber and an inclosed passage connecting the 70 interior of said first fume chamber with the exterior of 75 said casing.

Signed at Bellevue Pa., this 20 day of November 1906.

HENRY A. DENZIN.
